VALVE KEEPER INSERTER

Harry W. Kulp, Lancaster, Pa., assignor to K-D
Manufacturing Company, a corporation of
Pennsylvania

Application February 17, 1950, Serial No. 144,727

5 Claims. (Cl. 81—5.1)

1

This invention relates to valve keeper inserters for use in inserting and operatively positioning the usual removable split conical keepers about the valve stems of internal combustion motors.

The difficulties inherent in inserting and properly maintaining such keepers in position about their respective valve stems while lowering the valve springs and retainers are well known. Such difficulties have increased in recent types of automotive motors, due to the increasingly close spacing between the valve spring retainers and the tappets in these motors. This is particularly true in 1949 and 1950 Ford automobile motors.

The jaws of many keeper inserters heretofore known and used are so thick as to prevent their use in the limited space between the valve spring retainers and tappets of such motors, and the construction of these jaws is such that they would not function reliably if made thin enough to adapt them for such use.

With this in mind, it is a primary object of the present invention to provide a keeper inserter having a novel jaw construction which permits the jaws to be of exceedingly thin cross-section for use with such new types of motors without sacrificing strength and reliability of operation.

It is a further object to provide a jaw construction having the foregoing attributes which renders the tool capable of supporting itself and the valve keeper in operative position on the valve stem, leaving both of the operator's hands free to operate the valve spring lifter to lower the spring and retainer into operative engagement with the keeper.

A further important object is to provide such a tool in which each of the keeper positioning jaws employs but a single resilient gripping element arranged to rotate the keeper in an arcuate socket into tangential engagement with a fixed gripping element, said resilient element pressing against the keeper in a direction normal to and hence not directly opposed by the twisting force exerted by the weight of the tool when the latter supports itself on a valve stem.

Still further objects are: to provide in such a tool a novel form and arrangement of resilient gripping element; to provide guide means for preventing downward deflection or displacement of said element responsive to downward insertion of the keepers in the tool; and, to provide a novel laminated jaw construction wherein said guide means and various of the jaw parts or elements may be formed integrally and in preassembled relation in one of the stamped metal laminations, thus facilitating the production of such a tool and minimizing the cost thereof.

2

In this application I show and describe only the preferred embodiment of the invention, simply by way of illustration of the practice thereof as by law required. However I recognize that the invention is capable of other and different embodiments and that the several details of the invention may be modified in various ways, all without departing from said invention. Accordingly, the drawings and description herein are to be considered as merely illustrative and not as exclusive.

In the accompanying drawings:

Figure 1 represents a perspective view of a valve keeper inserter in accordance with the invention, having a pair of usual keepers operatively positioned and supported therein;

Figure 2, a fragmentary elevation showing the forward or jaw portions of the inserter tool together with the valve keepers positioned thereon;

Figure 3, an enlarged perspective view of the jaw portions of the inserter tool;

Figure 4, an enlarged cross-section on the line 4—4 of Figure 1, looking in the direction of the arrows;

Figure 5, an enlarged detail perspective view of the spring finger employed in the jaw construction; and,

Figure 6, an enlarged detail perspective view showing a sheet metal stamping or plate such as is employed in the jaw construction of the preferred embodiment.

In the accompanying drawings, the invention is exemplified in a tool embodying rigid levers 1 and 2 which are medially pivotally connected, as at 3, for relative pivotal movement in a lateral plane. The portions of these levers disposed rearwardly of the pivot 3 are formed to function as operating handles 4—4 for the tool, while relatively laterally opposed jaws 5—5 are provided at the respective forward end portions of said levers.

Preferably these levers 1 and 2 are of the non-crossing type so that movement of the handles 4—4 toward each other will separate the jaws 5—5, and to this end said levers may be provided with relatively overlapping medial projections 6—6 through which the pivot 3 is disposed.

A spring 7 coiled around the pivot 3 with its opposite ends pressing outwardly against the respective handle portions 4—4 exemplifies any of various means which are employed for normally urging the jaws 5—5 toward each other to maintain the tool in operative position about a valve stem or other work piece.

The said jaws 5—5 are respectively formed

with relatively laterally opposed arcuate or substantially semi-cylindrical recesses or sockets 8—8, the axes of which extend perpendicularly to the plane of movement of the levers 1 and 2. It will be apparent that the arcuate walls of these recesses 8, due to being integrally embodied in the respective rigid levers 1 and 2, are themselves extremely rigid and inflexible to provide firm supporting surfaces for engagement with usual split conical keepers K such as are used in the valve assemblies of late model automobile engines. Such keepers are usually provided with internal annular ribs or projections K' adapted for seating in an annular groove in a valve stem, as will be readily apparent to those skilled in the art.

Each said jaw 5 of the tool is provided with an arcuate keeper supporting ledge 9 projecting laterally inwardly at the bottom of its respective recess 8 to support a keeper K therein at a predetermined level. Such a ledge 9 in the preferred embodiment is defined by a portion of a flat metal plate 10 which is secured flush against the lower lateral face of its respective jaw 5, as by rivets 11 and 15, as shown. It is important of course that the ledges 9—9 of both jaws shall be at the same level to accurately position their respective keepers about the valve stem with the ribs K' of both in registry with the grooved portion of the valve stem and that the inner edges of these ledges shall not project inwardly beyond their respective keepers so as to interfere with the application thereof to the valve stem.

At one end of the recess 8 of each jaw is disposed a fixed keeper gripping or positioning element 12 which projects partially across said recess and in operation abuts against one circumferential end edge of the keeper to limit the rotary movement thereof in the recess 8. While such an element 12 may be formed in various manners, I prefer to form it as an integral upwardly bent portion of the aforementioned plate or lamination 10, and to dispose it longitudinally along the inner edge of its respective jaw adjacent the forward end of the recess 8 therein.

At the other end of the recess 8 in each of the levers 1 and 2 is disposed a movable resilient gripping or positioning element which may be in the form of a spring steel finger 13 extending longitudinally along the inner edge of and secured to its respective lever with its free end projecting partially across the recess 8 and resiliently tangentially deflectible relative to the arcuate wall of the recess 8, and to any keeper K disposed therein.

The function of this removable gripping element 13 of each jaw is to exert resilient tangential pressure against the circumferentially presented end edge of a keeper disposed in the recess 8 and to rotate such keeper into firm engagement with the fixed gripping element 12 at the other end of the recess. Thus the keeper K will be firmly frictionally gripped in the jaw between the two gripping elements 12 and 13, the keepers in both jaws being accurately supported at the same level by the ledges 9—9. Furthermore the keepers will be firmly maintained against displacement in their respective jaws except in an upward direction, and this will be permitted only upon the application of sufficient axial upward force to overcome the frictional grip of the two elements 12 and 13.

The spring finger 13 shown in the preferred embodiment is provided with relatively spaced

registering lateral ears 14—14 integral therewith and projecting from its medial portion to lie above and below the cooperating jaw 5 and plate 10 of its respective lever, a rivet 15 being passed through said ears 14—14 and the intervening lever and plate portions to firmly secure said lever in operative position. Preferably the inner edge of each lever 1 and 2 will be cut away adjacent the free end of its cooperating spring finger 13, as at 16, to avoid interference with the clamping or gripping action of said finger.

The rear end portion of each such finger extends rearwardly from the rivet 15, as at 17 and abuts against the inner edge of its respective lever to prevent retraction of the free end 13 from operative position by swinging movement of the finger about the connection 15.

Thus I provide a novel, simple and easily applied element 13 which will firmly and efficiently grip any keeper disposed in the jaw with which it cooperates, and which has no laterally projecting portions which might obstruct the closing movement of the jaws 5—5 about a valve stem.

It should be particularly noted that the two gripping or positioning elements 12—13 of each jaw are in substantial longitudinal alignment with each other on diametrically opposite sides of the respective recesses 8, so that when keepers are operatively positioned in these jaws any force tending to tilt said keepers about their axes in a plane longitudinally of the tool will be perpendicular to the tangential gripping force of each of the elements 13, hence will not be exerted directly on these elements or release their respective keepers.

In order to prevent downward deflection of the free forward ends of the spring fingers or elements 13, as might occur responsive to downward insertion of keepers into the jaw recesses 8—8, I provide guide plates or elements 18—18 respectively carried by each jaw and projecting laterally inwardly therefrom beneath the free end portions of the spring fingers. It will be seen that the lower edges of the spring fingers 13 may slidably engage these respective plates 18 and be deflected laterally thereacross during insertion of the keepers, while being positively maintained against downward deflection.

Such a guide plate for each jaw may be conveniently embodied in a laterally projecting portion 18 of the metal plate 10 of each jaw.

Thus the use of such a metal plate 10 permits the formation of the jaws of the tool in an extremely simple and economical manner, such a plate being easily produced by usual metal stamping operations and embodying the keeper supporting ledges 9, fixed gripping element 12 and guide plate 18 of its respective jaw in pre-assembled integral relation.

In the use of the invention, which is believed to be clearly apparent to those skilled in the art, the tool is loaded by spreading apart the jaws thereof and manually inserting keepers K into each of the jaw recesses or sockets 8, each keeper being placed over its respective recess 8 and rearwardly axially tilted so that its rear circumferentially presented edge abuts against the movable element 13, and then rotated against said element to deflect same sufficiently to permit insertion of the keeper into the socket or recess 8 with its other circumferential end edge in abutment with the fixed element 12, whereupon the keeper is pressed down until its bottom abuts against the supporting ledge 9. With the keeper

5

thus inserted in the socket of its respective jaw, the resilient element 13 will exert tangential pressure against same, tending to rotate and maintain it in firm engagement with the fixed element 12, thus the keeper will be firmly gripped between said elements 12 and 13.

In order to apply the keepers in operative position about a valve stem, as part of the operation of replacing the valve spring, the spring is raised and maintained in raised position on the valve stem by a usual valve spring lifter. With the spring in raised position, the jaws of the loaded inserter tool are spread in obvious manner and the keepers therein are placed on opposite sides of the valve stem with their inner projections or ribs K' in registry with the cooperating groove in the valve stem. The jaws are then permitted to close about the valve stem, applying the keepers K in proper position thereon. With the keepers thus applied, it will be apparent that the handles 4-4 may be completely released, and the tool will firmly and reliably support itself and the keepers on the valve stem, leaving both of the operator's hands free to then operate the valve spring lifter to lower the spring and its cooperating washer into operative relation about the keepers.

Such lowering of the spring and washers about the keepers will of course force the retainer tool downwardly about the valve stem and out of engagement with the keepers in known manner, so that it may be removed at the operator's convenience.

The self-supporting ability of the tool as above described arises from the particular arrangement of the tool so that the movable gripping elements 13-13 press against their respective keepers in directions normal to the twisting force exerted by the weight of the tool when same is applied to and projects radially from a valve stem. Thus such twisting force will not be exerted directly against the said elements 13 and in fact only a relatively small component of such force will be imparted to said fingers in a direction which will tend to reduce the grip of the fingers on their respective keepers. The particular construction and arrangement of the spring steel fingers or elements 13 also is of importance, inasmuch as such fingers are capable of exerting a strong gripping force on the keepers in the desired tangential direction relative to said keepers, but do not project laterally from the inner edges of the jaws to interfere with the closing movement thereof.

I claim:

1. A valve keeper inserter comprising a pair of levers and means medially connecting same for relative pivotal movement in a lateral plane, the rear ends of said levers comprising laterally opposed operating handles and the forward ends thereof comprising relatively movable jaw portions respectively formed with laterally opposed arcuate keeper recesses the axes of which extend perpendicularly to the movement of said levers, resilient means being associated with said levers for urging said jaw portions toward each other, flat sheet metal plates secured flush against the lower faces of the respective jaw portions and defining arcuate keeper supporting ledges projecting radially concentrically inwardly of said recesses, upwardly bent portions of said respective plates projecting longitudinally of the respective levers partially across said recesses from the forward edges thereof to define fixed keeper positioning elements, lateral guide plates integral with said respective plates projecting toward each

6

other from beneath the opposed inner edges of said levers rearwardly of said recesses, in combination with longitudinally extending resilient spring fingers secured against the inner edges of the respective levers above said guide plates, the free end of each said finger projecting forwardly partially across the recess of its respective jaw portion and being deflectible across the upper face of its respective guide plate tangentially to its respective recess, whereby said free end can exert a tangential force against a keeper element disposed in its cooperating recess to rotate said keeper element into firm engagement with its cooperating fixed positioning element.

15. 2. A valve keeper inserter comprising a pair of levers and means medially connecting same for relative pivotal movement in a lateral plane, the rear ends of said levers comprising operating handles and the forward ends thereof comprising relatively movable jaw portions respectively formed with laterally opposed arcuate keeper recesses the axes of which extend perpendicularly to the direction of relative movement of said jaw portions, resilient means associated with said levers for urging said jaw portions toward each other, flat sheet metal plates secured flush against the lower faces of the respective jaw portions and defining keeper supporting ledges projecting radially inwardly of said recesses, upwardly bent portions of said respective plates projecting longitudinally of the respective levers partially across said recesses from the forward edges thereof to define fixed keeper gripping elements, lateral guide plates integral with said respective plates projecting toward each other from beneath the adjacent inner edges of said levers rearwardly of said recesses, in combination with movable keeper gripping elements carried by the respective levers and projecting longitudinally thereof across said respective guide plates past the rear edges of the respective recesses, said movable gripping elements being deflectible on said guide plates tangentially to their respective recesses.

3. A keeper inserter comprising a pair of levers medially pivotally connected for relative pivotal movement, and means associated with said levers for resiliently urging the forward ends thereof toward each other, the rear ends of said levers comprising laterally opposed operating handles and the forward ends thereof comprising relatively laterally movable rigid jaws, said jaws being respectively formed with laterally opposed arcuate keeper recesses having axes perpendicular to the lateral movement of said jaws, each said jaw comprising a fixed keeper gripping element and a longitudinally extending resiliently laterally deflectible keeper gripping element secured against longitudinal movement and deflection on its respective jaws, said elements being disposed in relative longitudinal alignment on substantially diametrically opposite sides of their cooperating recesses and projecting partially thereacross, in combination with guide plates carried by said respective jaws beneath said respective deflectible keeper gripping elements to prevent downward deflection of the latter.

4. A keeper inserter comprising relatively opposed rigid jaws and means supporting same for movement in a lateral plane relative to each other, said jaws being respectively formed with relatively laterally opposed arcuate keeper recesses the axes of which extend perpendicularly to the relative movement of said jaws, and means for normally maintaining said jaws in relatively closed position, each said jaw comprising a fixed

keeper gripping element and a longitudinally extending resiliently laterally deflectible keeper gripping element secured against longitudinal movement and deflection on its respective jaw, said elements being in relative longitudinal alignment on their respective jaws.

5. In a keeper inserted comprising relatively laterally movable rigid jaws, each jaw being formed with an arcuate keeper recess in one edge thereof and having a fixed keeper gripping element projecting radially partially across said recess from the forward end thereof, the combination with each jaw of a resilient gripping finger extending along said edge of the jaw rearwardly of the recess and having a free end projecting forwardly partially across said recess for resilient deflection tangentially thereto, said gripping finger comprising integral relatively spaced lateral ears projecting therefrom intermediate of its length, said ears being disposed 10 15 20

respectively above and below said jaw and pivotally connected thereto, the rearwardly projecting end of said finger abutting against the adjacent edge of said jaw to prevent pivoting of said finger about the connection between said ears and jaw.
